UNITED STATES PATENT OFFICE.

ALBERT BROADMEYER, OF HARRISBURG, PENNSYLVANIA, ASSIGNOR TO THE W. O. HICKOK MFG. CO., OF HARRISBURG, PENNSYLVANIA, A CORPORATION OF PENNSYLVANIA.

PAPER-FEEDING MECHANISM.

Application filed September 8, 1921. Serial No. 499,831.

To all whom it may concern:

Be it known that I, ALBERT BROADMEYER, a citizen of the United States, residing at Harrisburg, in the county of Dauphin and State of Pennsylvania, have invented certain new and useful Improvements in Paper-Feeding Mechanism, of which the following is a specification.

The present invention relates to sheet feeding apparatus, and more particularly to the suction means which engages the individual sheets and initially moves them.

The primary object of the invention is the provision of simple mechanism that will have a relatively even action throughout its extent, said means being simple to construct and assemble.

In the accompanying drawings—

Figure 1 is a plan view of a portion of a feeding apparatus, showing the improved mechanism,

Figure 2 is a sectional view on the line 2—2 of Figure 1,

Figure 3 is a detail longitudinal sectional view on an enlarged scale through the suction means and associated parts.

Figure 4 is a cross sectional view on the line 4—4 of Figure 3.

Figure 5 is a detail longitudinal sectional view through the channeled rod conduit.

In the structure disclosed, a suitable frame 6 is employed, in which is mounted the usual vertically movable table 7 on which the pile of sheets to be fed is placed. Above the rear end of said table is located a driving shaft 8 having a longitudinal keyway 9. A feeding head 10 of cylindrical form is mounted on the shaft 8, being slideable along the same. It is held to rotate with said shaft by means of a key or feather 11 engaged in the way 9. The head is provided with longitudinally disposed sets of air intake ports 12, the sets or rows being disposed side by side, and each row opening into a chamber 13 preferably formed by drilling a series of longitudinal bores into one end of the head, said bores terminating short of the other end, as will be clear by reference to Figure 3. An exhaust passageway 14 is provided for each chamber 13, and has a port 15 opening into the central portion of the chamber, with which the passageway is associated. These passageways also open through the end of

the head 10, through which the chambers 13 open.

Mounted in the frame in parallel relation to the shaft 8, is an exhaust conduit 15^a that terminates in a longitudinal channel 16. This conduit 15^a is coupled up to any suitable air exhausting mechanism. Surrounding the conduit and slidable thereon is a sleeve 17 that covers the channel 16 and this sleeve is provided with a neck 18 having a passageway 19 therein that is in communication with the channel 16. The free end of the neck 18 terminates in a head 20 that is in the form of an offset collar 21 surrounding a hub 21^a that is integral with the rotatable head 10 and projects from the end into which the chambers 13 and passageways 14 are drilled. The collar 21 is maintained on the hub 21^a by any suitable means, as for example nuts 22 and the passageway 19 terminates in an offset intake port 23 that successively registers with the outer ends of the passageways 14 as the head 10 rotates. It will be evident by reference to Figure 3 that when one of the passageways 14 is in communication with the intake port 23, the outer end of the corresponding chamber 13 is closed by the adjacent face of the collar.

Assuming that there is a partial vacuum formed in the conduit 15, channel 16, passageway 19 and port 23, it will be obvious that as the head is rotated and the passageways 14 successively register with the port 23, air will be exhausted therefrom and from the chamber 13. Consequently if a sheet of paper is brought into contact with the under side of the head 10 it will be held against the same by the suction and will be carried in the direction in which the lower side of the head rotates. As the open ends of the passageways 14 pass the neck and collar they open to atmosphere, and thus the suction is broken. By having the passageway 14 communicate with the central portion of the chamber 13, a more equal exhaust of air takes place through the various ports of each row or set, thereby securing a more equal application of the holding power to the sheet. Obviously the structure is relatively simple and can be cheaply manufactured.

From the foregoing, it is thought that the construction, operation and many advan-

5 tages of the herein described invention will be apparent to those skilled in the art, without further description, and it will be understood that various changes in the size, shape, proportion and minor details of construction may be resorted to without departing from the spirit or sacrificing any of the advantages of the invention.

10 Having thus fully described my invention, what I claim as new, and desire to secure by Letters Patent, is:

15 1. In sheet feeding mechanism, the combination with a rotatable head having a plurality of air intake means each disposed longitudinally of its axis of rotation and said means being arranged around its periphery and adapted to be successively brought into coaction with a sheet upon the rotation of the head, of air exhausting means that communicates with the longitudinal central portion 20 only of each of said air intake means.

25 2. In sheet feeding mechanism, the combination with a rotatable head having sets of air intake ports disposed around its periphery, each set being located longitudinally of the axis of rotation of the head, and air exhausting means that communicates with the longitudinal central portion only of each set of ports.

30 3. In sheet feeding mechanism, the combination with a rotatable head arranged to be moved along its axis of rotation, and having a plurality of radially disposed air intake ports, exhaust ports communicating with the radial ports, and an exhaust head mounted on the rotatable head to permit the rotatable head to rotate relative to the exhaust head but to carry the exhaust head with the rotatable head when the rotatable head is moved along its axis of rotation.

35 4. In sheet feeding mechanism, the combination with a rotatable head having a plurality of longitudinally disposed air intake means located side by side around its periphery, of an exhaust passageway for each means having a central connection therewith, and an exhausting mechanism including an intake port with which the passageways successively communicate on the rotation of the head.

45 5. In sheet feeding mechanism, the combination with a rotatable head having a plurality of longitudinally disposed sets of air intake ports, a common chamber with which the ports of each set communicate, of an exhaust passageway for each chamber having communication with the central portion thereof, and an exhausting mechanism including an intake port with which the passageways successively communicate on the rotation of the head.

55 6. In sheet feeding mechanism, the combination with a rotatable head having a plurality of longitudinally disposed sets of air intake ports that independently open

70 through the periphery of the head, a common chamber for each set and with which the ports of said set communicate, an exhaust passageway from each chamber, a connection between each common chamber and its exhaust passage between the end ports communicating with the chamber, and means for successively exhausting air through said passageways and from the respective chambers as the head is rotated.

75 7. In sheet feeding mechanism, the combination with a rotatable head having a hub, said head having a series of suction passageways opening through its periphery and through the end having the hub, a stationary exhaust head carried by the hub having an intake port with which the passageways successively communicate during the rotation of the head, and means on the hub for taking up wear.

80 8. In sheet feeding mechanism, the combination with a rotatable head having longitudinal sets of suction ports, a chamber for each set of ports, an exhaust passageway for each chamber opening centrally thereinto and also opening through one end of the head, and an exhaust head at said end having an intake port across which the ends of the exhaust passageways pass as the head rotates.

85 9. In sheet feeding mechanism, the combination with a rotatable shaft, of a rotatable head carried thereby and shiftable therewith, said head having peripheral suction ports, and a non-rotatable head in which the 90 rotatable head is journaled and connected so that the two will move together along said shaft, said non-rotatable head having an exhaust passageway that communicates with the suction ports of the rotatable head.

100 10. In sheet feeding mechanism, the combination with a rotatable shaft, of a rotatable head carried thereby and shiftable therewith, said head having peripheral suction ports, an exhaust conduit located alongside the shaft, and a coupling between the conduit and head forming a bearing for the head and slidable along the conduit and shaft and surrounding the latter, said coupling having connection with the suction ports.

105 11. In sheet feeding mechanism, the combination with a rotatable shaft, of a rotatable head carried thereby and shiftable therewith, said head having peripheral suction ports, a channeled supporting rod located alongside the shaft, a sleeve slidable on the rod and covering the channel thereof, a neck carried by the sleeve and having a passageway therethrough, and a head on the neck provided with an intake port that communicates with the suction ports of the rotatable head, said heads being connected so as to be adjustable together along the shaft.

120 12. In sheet feeding mechanism, the combination with a rotatable shaft, of a head

- rotatable therewith and slidable therealong, said head having a plurality of longitudinal sets of intake ports, a chamber for each set of ports, and a suction passageway for each 5 chamber communicating with the central portion thereof and having an outlet through one end of the head, a channeled supporting rod located alongside the shaft, a sleeve slidable on the rod and covering the 10 channel thereof, a neck carried by the sleeve and having a passageway therethrough, and a head on the neck provided with an intake port that successively communicates with the passageways of the head as the latter is 15 rotated.
13. In sheet feeding mechanism, the combination with a rotatable head having a series of longitudinal chambers opening through one end and a series of exhaust passageways communicating with the chambers and opening through the same end, said chambers having open communication through the periphery of the head, and means for exhausting the air from the chambers 20 through the exhaust passageways, said means acting as a closure for the open ends of the chambers when the air is being exhausted.
14. In sheet feeding mechanism, the combination with a rotatable head having a series of longitudinal chambers opening through one end and a series of exhaust passageways communicating with the chambers and opening through the same end, said 25 chambers having open communication through the periphery of the head, and a second head at that end of the rotatable
- head through which the chambers and passageways open, said head having an exhaust port with which the passageways communicate, and said second head constituting a closure for the open ends of the chambers when in communication with these passageways. 40
15. In sheet feeding mechanism, the combination with a rotatable head having a hub and provided with peripheral air intake means opening through its ends, of air exhaust means surrounding the hub and communicating with the portions of the air-intake means that opens through the end of the rotatable head and adjustable means carried by the hub for maintaining a tight joint between the exhaust means on the hub and the head. 45
16. In sheet feeding mechanism, the combination with a rotatable head having a projecting hub at one end, and provided with peripheral air intake ports and exhaust passageways communicating with the ports and opening through the end of the head having the hub, a non-rotatable head journaled on and surrounding the hub, and means on the hub for retaining the non-rotatable head on the hub, said latter head having an exhaust 50 passageway that successively communicate with the exhaust passageways of the rotatable head as the latter rotates. 55

In testimony whereof, I affix my signature in the presence of two witnesses.

ALBERT BROADMEYER.
